UNITED STATES PATENT OFFICE.

CHARLES A. HEDDEN, OF OAK PARK, ILLINOIS, ASSIGNOR TO ARMOUR & COMPANY, OF CHICAGO, ILLINOIS, A CORPORATION OF ILLINOIS.

VANITY CASE.

Application filed December 21, 1925. Serial No. 76,572.

To all whom it may concern:

Be it known that I, CHARLES A. HEDDEN, a citizen of the United States, residing at Oak Park, in the county of Cook and State 5 of Illinois, have invented certain new and useful Improvements in a Vanity Case, of which the following is a specification.

My invention relates to toilet devices and more especially to cases for the carrying of 10 powder compacts, rouge or the like and commonly designated as compacts or vanity cases.

It has been customary to embody in such devices, a base and cover member hinged 15 together and having a flat bottom and top and substantially cylindrical walls meeting the bottom and top at a right angle, the closed case constituting in effect a short cylinder housing a compact of powder or 20 rouge with a mirror and perhaps a powder puff. It has been proposed to form the case with outwardly convex base and cover to simulate a watch case, thus avoiding abrupt angles and marginal thickness.

25 The present invention has for its objects improvements in vanity cases, preferably of the "watch" type, whereby to attain a more effective dustproof cooperation of the case walls, a convenient latching of the members, 30 a secure assemblage of the rouge or powder compact within the case and ease of replacement by refills, together with other advantageous features which will be readily apparent from an inspection of the improved 35 device.

In order that the invention may be readily understood a preferred embodiment of the same is set forth in the accompanying drawings, wherein—

40 Fig. 1 is a side elevation of the closed vanity case;

Fig. 2 is an enlarged vertical cross section;

45 Fig. 3 is a horizontal section on the line 3—3 of Fig. 2;

Fig. 4 is a fragmentary detailed section on the line 4—4 of Fig. 3; and

50 Fig. 5 is a similar section illustrating a modified mounting of the mirror.

It is to be understood that the drawing, serving as a basis for detailed description, is illustrative only and that the invention is not to be restricted beyond the appended 55 claims read in view of the prior art.

56 The improved vanity case comprises a

base member 11 and a cover member 12, double convex in contour. Each of the members have re-entrant peripheral portions as indicated at 13 and 14, terminating in cylindrical margins 15 and 16 whereby is 60 attained a structure of a minimum thickness about the edges combined with a sliding engagement of cylindrical walls 15 and 16 to provide a close sliding fit, thus precluding the escape of loose powder from 65 the case.

By the re-entrant contour of the base and cover members they are respectively provided with interior grooves 17 and 18 at the junction of the side walls with the bottom and top respectively. The members are hinged at 19 in a plane substantially equidistant between the grooves 17 and 18 whereby to permit a hinged movement between the members. A spring split ring 20 70 is resiliently disposed within the groove of the base, one terminal being reversely bent at 21 to project outwardly through a narrow slot 22 formed in the wall of the base member and then rebent inwardly and upwardly as indicated at 23 and again outwardly at 24 to form a detent to engage over a shoulder 25 of the cover member. 75

It will readily be understood that the detent 24 serves as an interiorly engaging catch 80 to hold the cover in closed position while the portion 21 forms exteriorly operable means for manipulating the catch.

The other terminal of the split ring 20 is deflected inwardly to an eccentric position 85 as shown at 26 and provided with a hump 27. A second hump 27^a may be advantageously formed on the split ring 20 intermediate its length.

The compact of powder or rouge 28, 90 mounted upon a dished plaque 29 is adapted to be received within the base member and to have its marginal portion in underlying engagement with the ring and its humped portions. This compact may be readily inserted and as easily removed for replacement

100 by slipping its margin beneath the ring opposite its terminals and then pressing outwardly upon the hump 27 of the ring so as to distort the ring sufficiently to permit the plaque to be snapped beneath the same at that side, the resilience of the ring holding the plaque and compact securely in place when permitted to assume its normal position. 105

A mirror 30 is adapted to be received within the concave cover member and to be held securely in place by a bezel ring 31, the marginal portion of which is snapped into the groove 18 of the cover; or as shown in Fig. 5, a second split ring 31^a may be employed to engage over the margin of the mirror 30^a.

I claim:

- 5 10. A vanity case comprising base and cover members hinged at one side, a compact-retaining ring disposed resiliently within the base and overlying the compact margin, one terminal of the ring formed to serve as a 15 cover-retaining catch and the other terminal movable radially of the base to clear the compact margin and permit removal and replacement of the compact relative to the ring.
- 15 20. A vanity case comprising base and cover members hinged at one side, a compact-retaining ring disposed resiliently within the base and overlying the compact margin, one terminal of the ring forming a cover-retaining catch and the other terminal normally spaced inwardly from the base periphery and overlying the compact but distortable outwardly to release and permit removal and replacement of the compact.
- 25 30. A vanity case comprising dish-like base and cover members hinged at one side, the base having a re-entrant margin forming an interior groove, a spring split ring resiliently disposed within the groove, one terminal deflected and offset to form an exteriorly operable interiorly engaging catch for the cover and the other terminal normally disposed eccentrically but distortable to permit a compact to be inserted into and removed from marginal underlying engagement with the ring.
- 35 40. A vanity case comprising double convex dish-like base and cover members hinged at one side, the base and cover having re-entrant cylindrical margins whereby to provide interior marginal grooves and sliding contact between the base and cover when closed, a compact-retaining split ring resiliently disposed within the groove of the base and having a terminal portion extending eccentrically from but distortable into the
- 45 50. A vanity case comprising double convex dish-like base and cover members hinged at one side, the base and cover having re-entrant cylindrical margins whereby to provide interior marginal grooves and sliding contact between the base and cover when closed, a compact-retaining split ring resiliently disposed within the groove of the base and having a terminal portion extending eccentrically from but distortable into the

centrically from but distortable into the groove, a compact marginally engaged beneath the ring within the base, a mirror-retaining ring disposed within the groove of the cover member, and a mirror marginally arranged beneath the ring within the cover.

5 10. A vanity case comprising double convex dish-like base and cover members hinged at one side, the base and cover having re-entrant cylindrical margins whereby to provide interior marginal grooves and sliding contact between the base and cover when closed, a compact-retaining split ring resiliently disposed within the groove of the base and having a terminal portion extending eccentrically from but distortable into the groove, the second terminal of the split ring deflected and offset to form a latching detent for the case at a point diametrically opposite the hinge, a compact marginally engaged beneath the ring within the base, a mirror-retaining ring disposed within the groove of the cover member, and a mirror marginally arranged beneath the ring within the cover.

5 10. A vanity case comprising double convex dish-like base and cover members hinged at one side, the base and cover having re-entrant cylindrical margins whereby to provide interior marginal grooves and sliding contact between the base and cover when closed, a compact-retaining split ring resiliently disposed within the groove of the base and having a terminal portion extending eccentrically from but distortable into the groove, the second terminal of the split ring deflected and offset to form a latching detent for the case at a point diametrically opposite the hinge, the ring also provided intermediate its terminals with an inwardly extending hump, a compact marginally engaged beneath the ring within the base, a mirror-retaining ring disposed within the groove of the cover member, and a mirror marginally arranged beneath the ring within the cover.

In testimony whereof I have hereunto subscribed my name.

CHARLES A. HEDDEN.
